UNITED STATES PATENT OFFICE.

JACOB SCHAUB, OF LOGAN, UTAH.

COMMUNION-SERVICE.

1,156,319.

Specification of Letters Patent. Patented Oct. 12, 1915.

Application filed May 8, 1912. Serial No. 695,832.

To all whom it may concern:

Be it known that I, JACOB SCHAUB, a citizen of the United States, residing in Logan, county of Cache, and State of Utah, have invented a certain new and useful Communion-Service, of which the following is a specification.

This invention appertains to a communion service, and, more particularly, to means whereby individual containers may be thoroughly sterilized after the containers shall have been used and without the risk of breakage or injury to said containers.

The administration of the sacrament in church services by the use of cups and glasses wherein the lips of the communicants are brought into contact with the cups or other containers, is highly objectionable upon sanitary grounds, and such practices have been condemned by medical and ecclesiastical authorities; but so far as I am aware no satisfactory devices have been proposed or employed to mitigate the objection. It is common to employ individual glass cups of small capacity, but such substitutes are open to objection upon hygienic grounds, for the reason that they require to be thoroughly washed and sterilized, are liable to be broken during the sterilizing process or when dropped upon the floor, thus entailing expense, and when filling or serving them the hands are brought into contact with said cups.

The object of this invention is to overcome the foregoing, and other, objections inherent in the service of the communion to an assemblage or congregation. Accordingly, the invention embodies means by which a number of individual containers may be rapidly sterilized and without requiring the hands of the operator to touch the containers either in sterilizing, filling or serving them.

In a practical embodiment of the invention, a number of containers are positioned in a carrying member, and a number of these members are assembled one upon the other in such manner that relative movement of the members to each other cannot take place, whereby a number of members loaded with the containers can be easily handled so as to place them within a sterilizing tank, withdraw them from the tank, or empty them of the water so that the heated surfaces will dry by exposure to the air.

It is preferred to assemble the carrying members for containers of one member to fit

or nest partly into the containers of an adjacent member or members, thereby securing such an arrangement of the containers that free spaces are left between their surfaces, through which spaces liquid is adapted to flow. During the sterilizing operation, water and steam are free to circulate within and without the containers; after removal from the sterilizing tank, the carrying members and containers may be turned over or inverted to drain off the water, and when it is desired to fill the containers with liquid, the nested carrying members and containers may be dipped into such liquid, thereby simultaneously filling the containers.

For convenience in handling the assembled carrying members and containers, it is preferred to lock said carrying members together, and, further, to so construct the carrying members that, when assembled or nested, no relative movement between the members can take place.

Other features of the invention, and the advantages thereof, will appear from the annexed detailed description.

In the accompanying drawings, I have illustrated one practical embodiment of the invention, but the construction shown therein is to be understood as illustrative, only, and not as defining the limits of the invention.

Figure 1 is a vertical section, partly in elevation, through a device for sterilizing a number of containers, said device being positioned within a sterilizing tank. Fig. 2 is a plan view of the device removed from the sterilizing tank. Fig. 3 is an enlarged vertical section through two of the carrying members for supporting the containers in nested relation; the plane of the section being indicated by the dotted line 3-3 of Fig. 2. Fig. 4 is an end view of the device shown in Fig. 3.

The device for sterilizing the containers embodies one or more carrying members A each of which is provided with a series of apertures *a*. As shown, each carrying member is a metal plate provided at its side edges with depending flanges *a'* and at its ends with legs B. The legs are integral with the plate, the latter being preferably composed of sheet metal pressed into the desired shape by suitable dies for rapidly and economically manufacturing the parts of the sterilizing device. The apertures *a* are punched or pressed in the metal of plate A,

it being preferred to surround each aperture with a depending flange a^2 , said flange a^2 being slightly conical in order that containers C will wedge or bind themselves into themselves into position within the flanged apertures of the carrying member. Obviously, each carrying member may have any desired number of apertures, but as shown in Fig. 2, the plate of member A is 10 provided with two rows of apertures, each row consisting of nine apertures.

Depending legs B are provided at the respective ends of each carrying member A, each leg B being in the form of a plate, the 15 length of which is equal nearly to the width of the carrying member. The legs B are provided at their side edges with flanges b, said flanges being slightly inclined and converging downwardly. In addition to the 20 side flanges b, the legs B are provided with lugs b', two of said lugs being employed on each of the depending legs B. The lugs are struck up from the metal composing the plate of leg B, and after cutting the plate, 25 the metal between the cuts is bent inwardly so as to result in the lugs b'. Said lugs are positioned intermediate the side flanges b and between the top and bottom edges of the plate, whereby the lugs are intermediate 30 the height of the leg.

The described construction of the carrying member provides for the assemblage of a number of containers in compact relation, said containers being practically nested together. In assembling the members, a member A is placed over a corresponding member A and lowered into position so that the 35 legs B of one member will fit against the outside surfaces of the legs B on the member below it, and, furthermore, the side flanges b of one member will fit into or between the side flanges b on the member below it. When 40 placing the members together, the upper member is lowered with reference to the lower member until lugs b' rest upon the plate of the lower member, thus limiting the downward movement of the upper member with respect to member below it. This construction allows the carrying members to be 45 assembled compactly, and when said members are fitted together no relative movement can take place between the members for the following reasons:—First, the overlapping legs B on adjacent members pre- 50 clude an endwise movement of either member in one direction or the other; second, the engagement of the side flanges b prevents any sidewise movement between the nested members, and the engagement of lugs b' on one member with the member below 55 it limits the vertical movement or displacement between the members. It is to be understood, accordingly, that the parts are so positioned that they cannot become accidentally separated during the operation of 60

manipulating or handling the device, and, furthermore, said parts are compactly arranged with relation to each other, whereby a large number of containers C may be easily and quickly handled for the several 70 purposes specified.

Each container C is composed of suitable material, such as sheet metal, preferably a metal which will not corrode or oxidize. The container is spun, punched or otherwise 75 manufactured so as to produce the containers in large quantities economically, and said containers are preferably of the tapering form shown in Figs. 1 and 3. The container is inserted into a flanged opening a 80 of the carrying member so as to be held frictionally therein, the taper of the container being such that it will be supported by the flanged opening intermediate the height of the container thereby leaving the upper and 85 lower parts of said container projecting beyond the upper and lower sides of the carrying member, see Fig. 3. The carrying members are so spaced apart, and the containers are suspended in such positions within the 90 carrying members that the lower part of the containers in one carrying member will fit or nest within the containers of the carrying member below it, as shown in Fig. 3. When properly assembled the nested containers will not be in contact on their opposing surfaces, that is to say, each container of an upper member will be suspended within 95 the container of a lower member with the surfaces of the two members free from contact, thus leaving a free space c between the 100 nested members.

Means are provided for locking the connected members so that the device may be handled as a unit when introducing said device into a sterilizing tank D, or withdrawing said device from said tank, or otherwise 105 manipulating the device, as for example when pouring water off the containers when sterilizing them, or when filling the containers by immersing the entire device in a suitable liquid. The plates A are provided with small apertures each having an offset or slot e' so as to produce what may be designated as key-hole slots, and when the plates 110 are assembled by positioning them one upon the other so that the legs B, their flanges b and the lugs b' operate to correctly determine the relative positions of said carrying members, then the key-hole slots in the several members are in alignment vertically. Locking rods E, E' are provided with shoulders e², and these rods are adapted to be 115 thrust downwardly through the aligned key-hole slots of the assembled members, the shoulders e² passing through the notches or offsets e' of the key-hole slots, after which the rods are turned part way around so as to move the shoulders e² out of register with the notches in the key-hole slots. The rods 120 125 130

are provided with collars *f* having set screws *f'*, and, furthermore, the rods are provided at their upper ends with arms *g*. After the rods have been thrust through 5 the key-hole slots of the carrying members and turned for the shoulders *e*² not to register with the offsets in said slots, the arms *g* are brought into alinement with each other across the carrying member, after which a 10 sleeve *g'* is adjusted from one arm to the other so as to span the space between the two arms, whereby the sleeve is adapted to couple the arms *g* and the locking rods *E*, *E'* so that the arms and sleeve will serve the 15 purpose of a handle in manipulating the connected series of carrying members and the containers therein.

It will be observed that shoulders *e*² of the locking rods are positioned below the 20 plate of the bottom carrying member, whereas the collars *f* are positioned on the rods above the uppermost carrying member, whereby the shoulders and collars are adjustable on the locking rods according to the 25 number of carrying members which are to be locked together, and the locking rods constructed as described are thus adapted for securely holding together any desired number of the carrying members. Thus, in Fig. 30 1 a series of six carrying members are held together by the locking rods, whereas in Fig. 3 the collars are adjusted on the rods to adapt them for locking together two of the carrying members.

35 In using the device for sterilizing and other purposes, a required number of containers *C* are placed within the apertures *a* of the bottom carrying member, and the same is true with respect to each of the other 40 carrying members. The carrying members loaded with containers are placed one upon the other by the legs *B* of one member fitting between the flanges *b* of the legs of the member below it, the lugs *b'* of one member 45 resting upon the plate of the lower member. The locking rods *E*, *E'* are inserted and turned, after which sleeve *g'* is adjusted to connect the arms *g* of the two locking rods, see Figs. 1 and 2. When thus assembled, 50 the carrying members are locked securely together and the containers are nested in a way to leave the free spaces *c* between the surfaces of the nested containers. The device may now be lowered into the sterilizing 55 tank *D*, and the cover *D'* placed upon said tank. The tank should be filled with water and placed on a stove or other heater so that the water will be heated, and the heated water and steam will fill the containers so 60 as to circulate through the containers and through the spaces *c*, thereby thoroughly sterilizing the containers. The device may be easily lifted out of the tank by the handle, and it may be turned over on the side 65 or inverted so as to drain off the water, these

operations being performed without displacing the containers from the carrying members.

The device may be used, also, for filling 70 the containers when assembled, as heretofore described and illustrated in Figs. 1 and 2. After the containers shall have been deposited in the carrying members, and said members are locked together by the rods, the entire structure may be dipped in a suitable 75 liquid, the latter being free to flow through spaces *c* so as to substantially fill the containers.

The entire device fulfills all the requirements from a sanitary standpoint, and it enables the work of sterilizing and filling the 80 containers to be effected collectively by very simple and efficient means.

Having thus fully described the invention, what I claim as new, and desire to secure by Letters Patent is:—

1. In a device of the class described, the combination of a plurality of container-carrying members positioned one upon the other, a plurality of locking rods passing 90 through end portions of said container-carrying members, each rod having locking engagement with said members, and a handle detachably connected to said locking rods and operating to retain said rods in locking 95 engagement with said members.

2. In a device of the class described, the combination of a plurality of carrying members positioned one upon the other, container members positioned in said members for the containers of one member to nest into the containers of another member, and means for retaining said carrying members in a connected condition to facilitate handling 100 thereof.

3. A device of the class described embodying a plurality of carrying members perforated for the reception of a number of containers, containers positioned in the openings of said members and supported thereby, the containers of one carrying member nesting within the containers of an adjacent carrying member, and means for locking the carrying members in such relation to each other that the containers supported by one carrying member are free from contact with the containers of a lower carrying member. 110

4. A device of the class described embodying a plurality of carrying members positioned one above the other, each member having openings, and containers fitted in said openings and supported by said members, the containers of one member nesting within the containers of an adjacent member, the surfaces of said nested containers being free from contact, thereby leaving free spaces between the nested containers. 120

5. In a device of the class described, the combination of a plurality of carrying members, and a plurality of series of containers 125

- supported by said carrying members, the containers of one series being nested with reference to the containers of an adjacent series, the surfaces of the nested containers being free from contact, thereby leaving free spaces between said nested containers.
6. In a device of the class described, the combination of a plurality of carrying members, a plurality of series of containers supported by said carrying members, the containers of one series being nested with reference to the containers of an adjacent series, the surfaces of the nested containers being free from contact, thereby leaving free spaces between said nested containers, and means for retaining the carrying members in connected condition whereby the device when loaded with containers may be manipulated as a unit.
7. In a device of the class described, a plurality of carrying members each provided with depending legs, the side edges of which are flanged, the legs of one member being slidably fitted to the legs of the member below it, the legs of the superposed member lying between the side flanges on the legs of the subjacent member.
8. In a device of the class described, a plurality of carrying members each provided with outwardly inclined depending legs, the inclined legs of one member being slidably fitted to the inclined legs of the member below it, and lugs extending inwardly from said depending legs and positioned intermediate the ends thereof for arresting the sliding movement of the members with reference to each other.

9. In a device of the class described, the combination of a series of carrying members positioned one upon the other, separate rotatable locking rods passing through end portions of said members, said rods having lugs positioned for locking engagement with the lower member and said rods being removable individually from said members, and a handle detachably fastened to said rods and retaining them in locked engagement with the carrying members.

10. In a device of the class described, the combination of a series of carrying members positioned one upon the other, said members having key-hole slots, and locking rods provided with studs, said rods and studs being adapted to pass through said slots and to detachably lock the members together.

11. In a device of the class described, the combination of a series of carrying members positioned one upon the other, said members having key-hole slots, and locking rods provided with studs, and with angular arms, said rods and studs being operable to lock the carrying members together, and means for connecting the arms of the locking rods whereby the connected arms are adapted to serve as a handle for manipulating the device.

In testimony whereof I have signed my name to this specification in the presence of two subscribing witnesses.

JACOB SCHAUB.
